[57] CLAIM

The ornamental design for a merchandise display shelf, as shown and described.

DESCRIPTION

FIG. 1 is a top plan view of a Merchandise display shelf, showing my new design;

FIG. 2 is a side elevational view, the opposite side being a mirror image thereof;

FIG. 3 is a bottom plan view;

FIG. 4 is a front elevational view;

FIG. 5 a rear elevational view;

FIG. 6 is a cross sectional view taken along line 6—6 in FIG. 6; and,

FIG. 7 is a view in perspective showing the interior of my shelf design.

FIG. 1

FIG. 2

FIG. 3

FIG. 4

FIG. 5

FIG. 6

FIG. 7
